UNITED STATES PATENT OFFICE.

SAMUEL T. HENRY, OF SOUTH BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

PROJECTILE.

1,248,656.

Specification of Letters Patent.

Patented Dec. 4, 1917.

Application filed June 28, 1913. Serial No. 776,410.

To all whom it may concern:

Be it known that I, SAMUEL T. HENRY, a citizen of the United States, and resident of South Bethlehem, county of Northampton, State of Pennsylvania, have invented a certain new and useful Improvement in Projectiles, of which the following is a specification.

This invention consists in a projectile having an attached base which is effective in operation and simple and economical to construct. The invention is shown diagrammatically in the accompanying drawing in which,

Figure 1 is a longitudinal section of a projectile having its base connected according to the present method;

Fig. 2 is a partial section illustrating the method of shaping the end of the shell and assembling the base before finally connecting the two together, as shown in Fig. 1;

Figs. 3 and 4 are sections similar to Figs. 1 and 2, but showing another form of the invention;

Figs. 5 and 6 are similar to Figs. 1 and 2 respectively and show still another form of the invention.

The invention consists in providing either the base or the body of the projectile with an annular under-cut portion and the part that is to be fitted thereto with a flange adapted to be rolled, compressed, or swaged into the under-cut portion to securely lock the two together. The part which is to be pressed into the under-cut portion is formed with sufficient metal so that when the operation is completed the projectile will have the usual cylindrical form at its base.

Fig. 2 shows one way of carrying out the method by forming the annular base plug B with an annular under-cut groove 10. This groove is so formed that the base will have an annular flange 11 at its rear side and an annular portion 12 at its forward side which tapers toward the flange 11. The shell body A is formed with an annular recess 13 which may be cylindrical in form and equal in diameter to that of the larger end of the part 12 of the base, so that said part will fit neatly into the annular recess 13, as shown in Fig. 2. The flange 14 surrounding the annular recess 13 is formed with an outward flare containing sufficient metal so that when the end of the shell body 55 is pressed into the groove 10 it will fill the

groove and leave the outer surface of the body flush with the outer margin of the flange 11 of the base, as shown in Fig. 1. The two parts of the shell are formed and assembled, as shown in Fig. 2, and then brought into the form shown in Fig. 1 by rolling, swaging or compressing the flange of the shell into the annular recess of the base plug. Any suitable apparatus or dies may be used for this purpose.

In Fig. 4, the shell body A is formed with an under-cut groove 15 at its rear end and the base B is formed with a flange 16 having a cylindrical inner wall and an excess of metal which will fill the groove 15 when the parts are rolled or swaged together.

The form shown in Figs. 5 and 6 is similar to that shown in Figs. 1 and 2, excepting that the flange 11 is omitted, the base or closure B being tapered rearwardly throughout its entire periphery. The rear end of the body is formed with an annular recess 17 adapted to receive the base and the flange 18 surrounding the recess is formed with an excess of metal which will fill out the base of the shell to the usual cylindrical form after the flange is swaged or pressed down upon the base B, as shown in Fig. 5.

In all three forms illustrated, one of the parts may be said to be under-cut and the other part provided with a flange adapted to be swaged or pressed into engagement with the under-cut portion of the mating part, the said flange having sufficient metal to fill out the base of the finished shell to the usual cylindrical form. Other forms of the invention may be used but the above will suffice to fully illustrate it.

It will also be noted that in the several embodiments of the invention illustrated, the cylindrical body has a substantially annular seat in a plane at right angles to its axis to receive the base and the base is fitted to this seat before the parts are swaged together, thus the parts are so formed that when assembled the projectile has the required dimensions, with a cylindrical body and flat base and needs little or no machining.

Having described my invention what I claim and desire to secure by Letters-Patent is,

1. A projectile having a hollow cylindrical body and a base, one of said parts hav-

ing an annular under-cut portion and the other having an annular surface fitting and dove-tailing with said under-cut portion, the cylindrical outer surface of the projectile extending to the plane of the outer surface of the base, the body of the projectile having a substantially annular seat in a plane at right angles to its axis against which the base abuts, substantially as described.

2. As an article of manufacture, a projectile body in the form of a hollow cylinder having an annular bendable flange on the end thereof, said flange being wedge shaped in cross section and outwardly flaring and having a cylindrical inner face.

3. As an article of manufacture a projectile body in the form of a cylinder having an axial recess therein opening at one end thereof, and an annular bendable flange 20 concentric with the axis of the projectile on said end, said flange being wedge shaped in cross section and outwardly flaring and having a cylindrical inner surface offset from the surface of the recess. 25

In testimony whereof I affix my signature in presence of two witnesses.

SAMUEL T. HENRY.
